UNITED STATES PATENT OFFICE.

NATHAN MUSHER, OF WASHINGTON, DISTRICT OF COLUMBIA.

PACKAGE-FILLING MACHINE.

1,131,727.

Specification of Letters Patent. Patented Mar. 16, 1915.

Application filed January 5, 1914. Serial No. 810,501.

To all whom it may concern:

Be it known that I, NATHAN MUSHER, a citizen of the United States, and residing at Washington, in the District of Columbia, have invented certain new and useful Improvements in Package-Filling Machines, of which the following is a specification.

This invention relates to package-filling machines, and more particularly to machines especially designed for filling cans with oil or other liquids.

The improvements are adapted for machines employing revoluble supports for the cans to be filled, and the main object of the invention is to provide novel and effective means for elevating the cans to the filling position and automatically lowering them to permit of their ready removal from the machine after filling.

20 The invention comprises a stationary cam shaped track-way in combination with a revoluble table, independent vertically-movable rods carrying wheels on rollers adapted to travel on said track-way, a valve controlling the flow of oil to the cans, and means for turning said valve by the revolution of the table.

The invention also includes novel means for holding the cans in position above the vertically-movable rods, said can holders being readily removable from the machine, and so constructed as to dispose of any overflow or drip from the can and thus prevent gumming or clogging of the holder.

35 The construction of the machine will be fully described hereinafter in connection with the accompanying drawings which form a part of this specification, and its novel features will be set forth and defined 40 in the appended claims.

In the drawing: Figure 1 is a top plan view partly in horizontal section of a machine embodying the invention. Fig. 2 is a vertical sectional view of the same. Fig. 3 45 is an elevation of the cam-faced track-way employed. Fig. 4 is a view in perspective of one of the improved can holders employed, and, Fig. 5 is a central vertical section of the same.

50 The reference numeral 1 designates a shaft revolubly supported in a bearing 2 and having a gear wheel 3 fixed upon its lower end meshing with a worm shaft 4 driven from a suitable source of power. A two- 55 part casing 5 provided with a ball-race 6 surrounds the lower portion of the shaft

and incloses the gear wheel 3 and worm shaft 4, the shaft having an annular shoulder 7 resting upon the ball-bearings 8. A spider hub 9 secured to the bearing 2 by a set screw 10 supports radial arms 11 to the outer ends of which is secured a circular track-way 12, the flange 13 of which has cam surfaces 14 dividing the flange into two track-ways of different height. A spider 60 comprising a hub 15 and radial arms 16 is secured to the shaft 1 by a set screw 17, and below these arms 16 is secured a ring 18 provided with guide openings 19 for a series of rods 20 said ring being secured to the 65 radial supports 16 by vertical supports 18a. To the lower end of each of the rods 20 is secured a block 21 to the outer side of which is journaled a grooved roller 22, said rollers being adapted to travel on the flanged track- 70 way 12.

At diametrically opposite points two vertical rods 23 are secured to the track-way 12 by U-shaped clamps 24 and set screws 25, said clamps each being provided with a 75 socket 26 to receive the lower ends of the rods 23, and securing set screws 27. At the upper end of each of the rods 23 is a collar 28 from which projects a pin 29 upon which is mounted a roller 30 adapted to be struck 80 by a tripping lever 31 pivotally secured to the stem 32 of a valve arranged within a casing 33 to control the flow of liquid through a filling spout 34 adapted to project 85 into the filling opening of a can 35 or other 90 container. The liquid supply is from a suitable tank or reservoir indicated as 36 in Fig. 2, and connected by a pipe 37 with the valve casing 33.

To the upper end of each of the rods 20 95 is removably-secured a package holder (in the present case a can holder), which constitutes an element of importance in the present invention, and comprises a base 38 provided with side flanges 39 constituting 100 guards, and projecting seats 40 to support the bottom of the can above the base on three sides, the front side of the can bearing against a stop 41 secured centrally between the side flanges 39, and secured by a 105 bolt or rivet 42. The upper side of the base 38 of the holder is inclined inward, and the inner ends of the flanges 39 converge to provide a trough-like dripping end for the holder. From the under side of the base 110 38 depends a socket 43 to receive the upper end of the rod 20, said rods being guided

through openings in a ring 44 secured to the outer ends of the spider arms 16. The arms 16 support a drip-pan 45 having a flared edge flange 46 and sleeves 47 surrounding the rods 20. The can holders are removably secured upon the ends of the rods 20 by set screws 46'.

The operation of the machine constructed as above described is as follows: The rotation of the shaft 1 revolves the can-holders and their supporting rods 20, and the rollers 22 travel around the circular cam-faced track-way, the cam surfaces 14 causing the raising and lowering of the rods, and the can-holders carried thereon. When the rod is in its elevated position, the filling spout 34 is projected into the filling opening in the can as shown at the left in Fig. 2, and when the rod is lowered by the dropping of the roller 22 to the lower level of the track-way as shown at the right in Fig. 2, the can is released from the lower end of the filling spout, permitting the filled can to be removed from its holder. The reservoir 36 and its discharge pipes are supported in any suitable manner. These elements, as well as the valve mechanism here shown, constitute the subject matter of a separate application for Letters Patent, and any other liquid supply means may be substituted for the means here shown, without affecting the operation of the vertically movable rods and their can-holders. The function of the rollers 30 is to trip the levers 31 or other valve-operating mechanism.

What I claim as new is:—

1. In a package-filling machine, the combination with a revoluble shaft, of a fixed circular cam-faced track-way, a hub se-

cured to said shaft, radial arms projecting from said hub, a flanged drip pan supported by said arms and formed with a central opening for said shaft and a row of openings formed adjacent the periphery of said pan, upwardly projecting sleeve guards for each of said openings, a series of vertically-movable rods extending through said row of openings, a ring supported below said pan and formed with guide openings for said rods, rollers carried by the lower ends of said rods adapted to travel on said track-way, and a series of holders supported upon the upper ends of said rods.

2. A can-holder for filling machines, comprising an inclined base having side guards or flanges converging at their inner ends, and projections on said base to support a can above the inclined surface of the base.

3. A can-holder for filling machines, comprising an inclined base provided with side flanges converging at their inner ends, projections on said base to support a can above the latter, and a stop adjacent the inner end of said base to engage the can.

4. In a can-filling machine, the combination with a supporting rod, of a can-holder comprising a base having a depending socket to receive the upper end of said rod and side guards converging at their inner ends, projections on said base to support a can above the upper surface of the base, and a stop to limit the inward movement of the can.

In testimony whereof I affix my signature in presence of two witnesses.

NATHAN MUSHER.
